UNITED STATES PATENT OFFICE

NICHOLAS AKIMOFF, OF ROME, ITALY

SHIP'S STRUCTURE

Application filed December 14, 1928, Serial No. 325,982, and in Italy October 30, 1928.

These improvements relate more particularly to the rear end of the vessel, called generally the afterbody (the run). It is usual in the art of naval construction to make this as fine as possible, always, but especially so for the high speed vessels, while for the slow speed ships, such as cargo boats or oil tankers etc., the requirements of great displacements necessitate this being made much fuller, but still with the view of making it as fine as the conditions permit. While there is no rigid demarkation line, everyone can differentiate a fine lined vessel from a full lined one.

It is natural to feel that the fine lined vessel is better adapted for high speeds, but there is also a theoretical reason by which this is generally justified as follows: if we make a void or empty space just below the water surface, by rapidly moving through the water an object (of any kind), the water will have a tendency to close in at a velocity of approximately

$$v = \sqrt{2gh} = \sqrt{19.62 \times 10.33} = 14.12 \text{ metr. per sec.}$$

or = 46.4 feet per sec. or = 27 1/2 knots (in reality this will be less owing to several correction factors etc.). In connection with the foregoing formula it should be noted that the constant 10.33 is in meters and represents the height of a column of water balancing or equivalent to the atmospheric pressure. In other words if the lines of the vessel's afterbody were full, or if the stern were cut off sharply, the water near the surface could not close in (even theoretically), and there always would be a cavity, aft of the vessel's stern. But at the depth of 10 m. the velocity with which the water would tend to close in would be

$$v = \sqrt{19.62 \times 20.33} = 20 \text{ m. sec.} = 65.6 \text{ feet sec.}$$

or about 39 knots. So that even taking into consideration various correction factors, the void or vacuum could not form even at very high speeds aft of the deeply submerged part of the vessel. Of course the mechanism of the closing in is much more complex and can be more fully explained only by the formation of vortices aft of the hull, as set forth in the Karman's theory of resistance according

to which (Fig. 1 of the accompanying drawings) the body moving along the direction of the arrow A loses a certain amount of vortices, which also move in the same direction, but at a smaller velocity and thus break away from the body. The mutual distances between these vortices and the rate at which they form and break away from the hull enable (at least in theory) an idea to be formed of the resistance of the hull (introducing, of course, many other factors, such as skin friction, with which we are not concerned in this discussion). The most important fact is that this theory supplies a certain amount of information regarding the wake, that is the water aft of the ship which tends to close in and thus gives a certain forward push to the hull; thereby diminishing its resistance to forward motion. It is well known that in fine lined ships this wake effect is negligible or vanishes altogether. Now, while this is necessary for the part of the hull located near the surface of water, this may be altogether unnecessary for the sections or portions located deeper, which if made fuller would bring about the wake effect without any danger of forming cavities aft of the hull.

The present invention consists in constructing the afterbody of the ship in such a manner that the lines of the portions at the water line and immediately below it, are of the "fine" type, and become fuller, than permits the present usual practice, as the depth increases. Everyone who has had experience with ship's models knows that at low speeds the finer lined model requires relatively more power, and its only object is to permit of attaining higher speeds. With my construction, though, this is partly remedied, and a hull which above the surface may look as fine as that of any high speed vessel of today, may have in reality a much fuller submerged part of the afterbody, and for this reason may be much more economical for both the lower and the higher speeds.

The invention is clearly illustrated in the accompanying drawings, in which:—

Fig. 1 shows the formation of the wake aft of the ship constructed in accordance with the present invention,

Fig. 2 is a diagrammatic view showing the buttock lines of the pipe,

Fig. 3 is a similar view showing the water lines of the pipe,

5 Fig. 4 is a cross-section of the ship's afterbody, and

Fig. 5 shows a construction known as blisters appearing to be similar to but having nothing to do with the present improvement.

10 In the accompanying drawing I have taken an afterbody of a full lined vessel, whose original lines are shown in dotted (or in thin) lines, and have modified its form as shown by heavy full lines. My afterbody therefore comprises a combination of fine 15 lined one at the water surface and a little below it, and of a fuller lined one, below a certain depth (say $\frac{1}{4}$ or $\frac{1}{3}$ of the total depth of immersion draft). If the economical speed 20 of the original vessel, from which this sketch was made, was say 12 knots, the speed of the modified vessel will probably be 14 knots or so. Of course, the belt, connecting the two radically different surfaces, the fine lined 25 one and the full lined one, must be worked out in a very careful and gradual manner, but to those versed in the art this will not present any special difficulties. For very high speed vessels, transatlantic liners or 30 cruisers, the actual curves may look different, but exactly the same idea will be maintained: perhaps in some cases the lines of the upper sections, just below the water line, will be made still finer than now, which 35 would be beneficial from the standpoint of wake formation, but the more submerged portions would be made much fuller than they would be at present, thus materially reducing the resistance. The appended 3 views 40 illustrate the exact manner in which the lines are made fuller in the lower section, and finer in the upper ones.

It is evident that the propellers for the afterbody will have to be designed differently from the manner in which they would 45 be for the same vessel with the afterbody of the usual type, but this is a matter that does not concern us in the discussion of the lines of the ship itself.

50 The drawing shows the application of this principle to single screw vessels, but it is clear that the same principle without any modification whatever, is applicable also to multiple screw ships with the added advantage that the appendages (bossing)—owing to the fuller form—would be shorter and thereby would offer less resistance. There are special forms of vessels, as illustrated in Fig. 5 seldom used, but although 55 enlarged at the midship section, they have the afterbody of the usual type, that is as fine as the conditions permit; for this reason these vessels have nothing in common 60 with the present invention, which applies to

them exactly in the same manner as it does to any other type of vessels.

Having now particularly described and ascertained the nature of my said invention and in what way the same has to be performed, I declare that what I claim is:

70 1. A ship's form comprising an afterbody composed of two types of curved surfaces: a finer body being the upper, and the fuller lined body being the lower, suitably connected by an intermediate belt of compound curvature, located below the load waterline.

2. A ship's form according to claim 1, whose waterlines are relatively finer near the surface of the water, and are relatively 80 blunter at greater submergence.

3. A ship's form according to claim 1 in which the transverse sections of the afterbody have a point of inflection below the load waterline.

85 4. A ship's form according to claim 1 whose buttock lines have a point or region of inflection below the load waterline.

5. A ship's form according to claim 1 wherein the afterbody is constructed in a 90 manner to cause greater wake at regions of greater submergence than nearer the surface.

6. A ship's form according to claim 1 in which the transverse section and the buttock lines of the afterbody are interrupted in their natural curvature at a certain depth below the load waterline, and become after that point, fuller than they would be if the natural curvature was continued in the usual manner.

95 In testimony whereof I have hereunto set my hand.

NICHOLAS AKIMOFF.
